E. KNAUER

ORE REDUCING PROCESS

Filed Dec. 9, 1920

INVENTOR:

Ernst Knauer

UNITED STATES PATENT OFFICE.

ERNST KNAUER, OF LOS ANGELES, CALIFORNIA.

ORE-REDUCING PROCESS.

Application filed December 9, 1920. Serial No. 429,526.

To all whom it may concern:

Be it known that I, ERNST KNAUER, a citizen of the United States, residing at Los Angeles, in the county of Los Angeles and State of California, have invented a new and useful Ore-Reducing Process, of which the following is a specification.

This invention relates to processes for separating gold from other ores or sand, and to processes for separating different ores.

One object of this invention is to separate the gold from gold-holding sand along the beach.

Another object is to provide such a process adapted for separating gold from the tailings in gold mines.

Another object is to provide such a process adapted for separating certain ores, which would destroy the compound mixture, (used in a cyanide process for separating gold from the tailings) from the tailings before the tailings reach the cyanide receptacle.

Another object is to separate gold from beach-sand, which contains other ores besides gold, by the use of the cyanide process.

Another object is to provide a process by which precious metals may be procured and separated from other matter through use of the cyanide process.

Another object is to separate iron magnetically from gold-containing matter before subjected to a cyanide process.

Another object is to dry and heat wet matter to be dried before passing over magnets.

Another object is to provide igniting and burning means by which combustible matter can be burned and reduced to such an extent that a cyanide process is made more effective with the remaining matter.

Other objects will appear from the following specification and appended claims as well as from the accompanying drawings, in which—

Fig. 1 is a side elevation of a device roughly outlined, a few parts being removed from the front so as not to cover important details in this view.

Fig. 2 is a top plan view of the device. This device is merely illustrated to facilitate the description of the process disclosed herewith, and I wish it understood that I do not limit myself to this particular

structure and that slight modifications may be provided as long as the whole structure can produce the process.

In the drawing, 3 designates a conveyor for elevating or bringing the material up to a suitable point. 4 is a second conveyor, preferably used for distributing and drying the material.

It is well known that gold-holding sand very often holds other ores at the same time, thereby making it hard or sometimes even impossible to reduce such ores under a cyanide process. The cyanide process is preferably only used where no dissolvable non-precious metals are present, since such metals tend to destroy the cyanide to such an extent as to make such process too costly. The main point of this invention involves therefore mainly a process to reduce the ores in a manner as to make an elimination of such dissolvable non-precious metals and materials possible before the ores reach the cyanide compartment of such an ore-reducing plant or device.

Tailings are normally damp, and must be treated accordingly. Beach-sand is naturally also damp and to be treated in a similar manner. Under such conditions, the ore-containing or holding matter must naturally be dried when reduced in the manner disclosed in this application as will be more fully explained hereafter. For these several reasons I refer to a drying of the materials in the beginning of this description.

The material is then passing under a distributing and evening knife or blade 5. Handwheels 6 are provided for setting and controlling the blade 5 a suitable distance above the conveyor 4 so as to allow an even amount of material to pass between the blade 5 and the conveyor 4, striking off the material above such level, naturally serving to control the material to be handled, and facilitating the operation so that the material passes through the device to such an amount as to make a handling at the several different points of operation possible and suitable, as far as the conditions in the succeeding points of operations are concerned. If, for instance, the material is being fed at such a rate that no proper results and function can be obtained at a succeeding point of operation, such a feeding must then naturally be so controlled and regulated by such distributing and evening

knife that better accomplishments appear possible.

Two rollers 7 are arranged a suitable distance from and below the end of the conveyor 4 so that the material from the conveyor can fall and pass over the rollers 7.

Burners 8, preferably gas-tubes arranged above and closely disposed in relation to the periphery of the rollers 7, serve to ignite and consume combustible matter in the material passing through the device. The rollers are preferably turned and operated in the direction of the arrows 9 so that an even sheet or amount of material will pass over the rollers to the succeeding point of operations, but, of course, such an arrangement may easily be modified without changing anything in particular as far as this invention is concerned. In passing coarse material through this device, the rollers may easily serve to crush the material by turning the rollers in an opposite direction to the arrows 9 so that the material must pass downwardly between the rollers, as will easily be understood.

A conveyor 10 is disposed below the rollers 7 so as to receive the material from the rollers.

A second distributing and evening knife 11 is disposed in suitable relation to the conveyor 10 to control the material passing over the conveyor 10.

Magnetized rollers 12 and 13 are disposed across the conveyor, above the conveyor so that any matter of a nature that it can be influenced by magnets may be affected so as to accumulate on the rollers 12 and 13 drawn from the material passing under the rollers 12 and 13 on the conveyor 10. The ends 14 of the magnetic or magnetized cores or bars are provided with suitable shafts 15 journaled in the bearings 16, see Fig. 2. The magnet-coils 17 are provided for magnetizing the bars or members 12 and 13, forming at the same time the support for the other ends of the members 12 and 13, the members 12 and 13 projecting towards or into the coils.

The bars 12 and 13, being of magnetic material or magnetized by the coils 17, naturally attract any soft iron or any other materials which can be attracted in such a manner from out of the material on the conveyor 10. Since the members 12 and 13 rotate, they naturally accumulate such magnetically influenced material on their whole surface.

To keep the bars powerful, or in other words free from such material, at least on the underside, so as to make it possible for the bars to attract such material from the passing conveyor when the unseparated material is passing below the bars 12 and 13, magnet-cleaning means are provided. Preferably sharp-edged bars 18 are disposed

along the sides of the bars 12 and 13 resting against the surfaces of the bars 12 and 13 so as to scrape or remove the accumulated materials from the bars 12 and 13 before the same points of the bars 12 and 13 are again turned towards the lower side near and above the conveyor 10 to be in a position to attract more such materials from the unseparated mass on the conveyor.

The remaining material on the conveyor 10 then passes into the receptacle 19, which may be prepared for the cyanide or oil-flo-
tation process or any other similar process for reducing gold-containing ore.

Materials influenced by the magnets pass from the bars 18 to cross conveyors 20 and further into another receptacle 21.

In this manner ore can be reduced so that the different substances contained in the original material is delivered in separated form after passing through this device.

By letting the material pass over the rollers 7 when putting fine material, tailing or fine beach sand, through the device; or by reversing the turning direction of the rollers and forcing the materials through between the rollers, when putting coarser materials under treatment through this device, an even, fine or suitable stream of material is allowed to fall upon the next conveyor 10. A similar striking, distributing, or layer-equalizing is accomplished by the blade 11. In this manner the handling of ore can be so controlled that a suitable amount of material in suitable form can be provided at the several points of operations to facilitate the proper separating and reducing of the ore.

The rollers 7 are preferably hollow for eventual heating and drying purposes in addition to the drying by the burners 8. A heating plate 22 is provided under the conveyor 4 for drying especial wet ore-containing sand before reaching the layer-equalizing blade 5 and before passing under the burners 8. Combustible matter is naturally consumed under the burners 8, and, to facilitate a separating of the ore, a suitable fan 23 is provided sidewise of the rollers 7 in a position to blow ashes and combustible matter from the conveyor and rollers before the material passes under the magnets.

Having thus described my invention, I claim:

1. An ore-reducing process consisting in first subjecting wet ore to drying, then striking off an even layer of ore, then subjecting this dry and evenly conveyed material to open flames for burning combustible matter and at the same time fanning across the path of the burning and conveyed material so as to eliminate waste from such combustible matter, then separating matter from the ore magnetically.

2. An ore-reducing process consisting in

first subjecting wet ore to drying, then striking off an even layer of ore, then subjecting this dry and evenly conveyed material to a treatment under open flames for igniting and burning combustible matter and at the same time subjecting the material to a fanning treatment for removing the waste from the combustible matter, then striking off an even layer of material, and

subjecting this even layer to magnetic separators. 10

In testimony that I claim the foregoing as my invention I have signed my name in the presence of two subscribing witnesses.

ERNST KNAUER.
